STOP CONTROL MECHANISM

Max Richter, West Reading, Pa., assignor to
 Textile Machine Works, Wyomissing, Pa., a corporation of Pennsylvania

Application December 15, 1937, Serial No. 179,807

10 Claims. (Cl. 66—89)

This invention relates to knitting machines and more particularly to auxiliary stop means for yarn carrier bars or rods for limiting the traverse of one or more of the carrier rods at desired periods in the cycle of automatic or semi-automatic knitting machines.

In the automatic or semi-automatic operation of full-fashioned knitting machines, it is desired to begin knitting a second blank immediately upon finishing the knitting of a previous blank and without delaying operation of the machine to reset certain of the mechanisms. In order to accomplish this, it is necessary to begin knitting the second blank while the ordinary end stops for the yarn carrier rods are being moved relatively to each other. This is because the two ends of the blank are of markedly different widths and the end stops must be moved after a blank is finished before they can be used in the process of making the next one. Consequently, it has been proposed to employ an auxiliary stop means which is thrown into operation at or toward the end of each blank-knitting cycle to permit continuous operation of yarn carrier rods or bars during the resetting of the end stops.

It is an object of the present invention to provide a novel and efficient auxiliary stop arrangement for the yarn carrier rod or rods in use at the time the end stops are being moved.

Another object of the invention is to provide auxiliary stop means adapted for use not only at the time in the cycle that the end stops are being reset but also at other times in the cycle as desired.

Another object of the invention is to provide auxiliary stop means including members individual to the rods and adapted to coact with a plurality of yarn carrier rods simultaneously or to permit a stop member for a yarn carrier rod to be lifted when desired to permit the rod to move without hindrance from the member.

It is another object of the invention to provide a stop mechanism adapted to permit a carrier rod to make a complete yarn laying stroke at its initial movement away from the laid out position.

With these and other objects in view, which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

An apparatus in accordance with the invention comprises, together with the necessary means for

forming and interengaging the loops, a set of stop members mounted to move at right angles to the paths of the usual yarn carrier rods or bars and adapted to engage at desired times with projections on a rod or rods to limit their traverse when operated by a friction box or boxes or to hold a rod or rods in laid out position. Preferably, the invention includes an auxiliary cam shaft designed to operate in step-by-step fashion, the racking or stepping of which is activated from a main rotating cam shaft but controlled by a pattern mechanism such as the usual pattern chain. The auxiliary cam shaft has an auxiliary pattern member thereon which may be in the form of a chain.

I prefer to make the stop device for limiting the traverse of a carrier rod in both directions as a pair of stop members and to provide only one stop member, similar to one of said pair, in cases in which it is desired only to retain a carrier rod in some given position such for instance as the laid out position. Preferably, springs are provided for urging the stop members into position to engage the projections on the carrier rods and the stop members have means, as for instance hooks, attached thereto whereby a member may be withdrawn individually from engagement with its corresponding projection, either by hand or otherwise.

Means are provided whereby all the stop members may be moved in unison under the control of the auxiliary pattern member and it is preferred that the stop member or members for the yarn carrier rod or rods which are active during the knitting of the welt or which are held in a laid out portion have three positions, in one of which they are free of the projections on the rod or rods, in another of which they engage a longer of two projections on the rod or rods and in a third of which they engage both a longer and a shorter projection on the rod or rods.

A particular exemplification of the invention is illustrated in the accompanying drawings, in which,

Figure 1 is a front elevation of a portion of a full fashioned knitting machine to which my invention has been applied;

Fig. 2 is a transverse sectional view of the machine shown in Fig. 1, taken at a point intermediate to the needle banks;

Fig. 3 is a fragmentary sectional view taken on a different section plane from Fig. 2 but illustrating certain parts shown therein and on a larger scale;

Fig. 4 is a sectional view on the line 4-4 of Fig. 3 looking in the direction of the arrows;

Fig. 5 is a view somewhat similar to Fig. 4, but showing the parts in different positions;

Fig. 6 is a view of part of Fig. 3 looking in the direction of arrow A;

Fig. 7 is a fragmentary sectional view taken substantially along the line 7-7 of Fig. 3.

Figs. 8, 9, 10 and 11 are diagrammatic views illustrating a cycle of operations carried out by the apparatus of my invention; and

Fig. 12 is a plan view of a full fashioned leg blank alongside of an auxiliary pattern chain such as may be used in connection with my invention.

In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines", copyright 1920, and in the "Reading" Full Fashioned Knitting Machine Catalogues, copyright 1929 and 1935, published by the Textile Machine Works, Reading, Pennsylvania, and in a pamphlet entitled "Knitting Machine Lectures", published in 1935 by the Wyomissing Polytechnic Institute, Wyomissing, Pennsylvania.

The machine illustrated in the drawings is in general a "Reading" type full-fashioned knitting machine but having certain automatic features added thereto. The machine shown has a frame 10 including a center bed 11. A main cam shaft 12 designed to rotate continuously during the operation of the machine is journaled on the frame 10 while loop forming means 14 of ordinary type are shown (Fig. 2) supported from the center bed 11 and knitting means of ordinary type including needle bars 15 are shown connected to receive knitting movements from cams on shaft 12 through rollers on levers 16 and 17 of usual form and the ordinary connections thereto. Yarn to be knitted by needles on bars 15 is laid in the usual way by yarn guides or carriers on a group of yarn carrier rods or bars mounted to reciprocate in brackets 19 fixed to bed 11. The rods are usually referred to as rods 1 to 8 beginning at the rear or at the left when viewed from the left end of the machine or as shown in Figs. 2 and 3. The traverse of the rods when knitting is limited at one or both ends by end stops 20 carried on end stop nuts 21 and when it is desired to decrease the distance between the outer selvage edges of the fabric being knitted, the nuts 21 are moved toward each other automatically by known means, preferably by threaded spindles 22 (Fig. 8), one at each end of the machine, which are actuated by impulses received from cam 23 on the cam shaft 12 under control of a usual pattern mechanism 24 including a pattern chain 25. When the pattern mechanism permits, an impulse from cam 23 is transmitted through an arm 26 to mechanism 27 which is adapted to rack the spindles 22 to move nuts 21. When the machine has finished a given blank it is then necessary to reset the nuts 21. In order not to interrupt the operation of the machine, the resetting operation is performed automatically by the mechanism 27 (Fig. 1). The mechanism 27 illustrated is not part of this invention and is not claimed herein, but is further illustrated and described as well as claimed in Patent No. 2,109,140 issued Feb. 22, 1938, upon the applica-

tion filed by Max Richter and Julius Bareiss on May 28, 1935, Serial Number 23,834.

At the same time that nuts 21 are moved toward each other, the mechanism 27 actuates reversely threaded spindles 28 to draw toward each other the pairs of nuts 29, one pair at each end of the machine, to actuate narrowing rods 30 to move the narrowing combs 31 toward each other at the time they are raised after being first dipped by a narrowing machine including a front narrowing shaft 32 from which rods 30 are supported by brackets 33. Shaft 32 may be dipped when desired in the usual way by cams on shaft 12. The nuts 29 are moved apart or reset at the same time as the nuts 21 by mechanism 27 from a position they occupy at the end of one blank to a position they occupy at the start of the next blank. The impulses for causing a narrowing movement of nuts 29 and combs 31 come from cam 23, the same as those for nuts 21. The impulses for resetting the nuts 21 and nuts 29 by means of mechanism 27 originate from a cam 33 on shaft 12. Cam 33 is a double lobed cam so that it delivers twice as many impulses per revolution of shaft 12 as cam 23 and thereby resets the spindles 22 and 28.

During the period in which the resetting of stops 20 and nuts 21 occurs, an auxiliary stop means must be employed and an auxiliary stop means or mechanism 34 (Figs. 1, 2 and 3) is illustrated for limiting the stroke of the yarn carrier rod or rods used during such period. Mechanism 34 includes stop members 35. A pair of members 35 are provided for each carrier rod which may be employed for knitting during the period of resetting nuts 21 and nuts 29, but where a carrier rod is only to be held in laid out position by the stop mechanism only one stop member 35 need be employed for it. The stop members 35 are shown mounted to reciprocate in transverse slots in a block 36 and held in place by side plates 37 fixed to block 36 by screws 40. Block 36 is so mounted that stop members 35 lie each in the plane of a carrier rod and each carrier rod intended to cooperate with one or more stop members 35 has one or more dogs thereon. As shown, only the carrier rod 3 is intended to lay yarn during the resetting of the end stops 20 and combs 31, the rod 3 being shown in Figs. 3 and 4 as having two dogs 41 and 42 thereon for cooperating with a pair of stop members 35. The carrier rod 3 is intended to be laid out, when not in operation, on the right hand side of the machine. When it is picked up by the friction box at the beginning of a period in which it is to lay yarn, usually at the beginning of the welt portion of the fabric, the carrier rod 3 must pass beneath the right hand and left hand end stops for the rod as shown in Fig. 8. The end stops 20 for the carrier rod 3 therefore are raised at this time to the necessary height by automatic means not shown herein but shown and described in said patent by Richter and Bareiss. Stop members 35 being centrally placed, the left hand dog 42 must pass beneath the members 35 and these stop members are shown in Fig. 8 at a height permitting dog 42 to pass therebeneath to permit the yarn carrier rod to make a full yarn laying stroke on its initial movement away from its laid out position and the dog 41 must engage the right stop member 35 to properly position the left hand travel of the carrier rod 3. Dog 41 is therefore made higher than 42 so that it strikes a stop member 35 when the stop members are in the position shown in Figs. 8 and 9. The nuts 21

not being sufficiently far apart to give room for laying a welt, the stops 20 must be retained in elevated position until nuts 21 have been moved sufficiently far apart to bring end stops 20 to the proper positions. The carrier rod therefore passes beneath the left hand stop 20 on the initial left hand stroke of the rod as shown in Fig. 9. On the return stroke, the nuts 21 still are not in the desired positions, so the end stops 20 are maintained in their uppermost position and the carrier rod passes beneath the right hand end stop 20 as shown in Fig. 10. By this time, however, the stop members 35 have been lowered sufficiently to engage the shorter dog 42 as shown in Fig. 10, thereby properly locating the right hand selvage travel of the carrier rod, shortly after which, the nuts 21 having been moved as far apart as necessary, the end stops 20 are dropped and the central stop members 35 are raised as shown in Fig. 11 so that the auxiliary stop means is no longer effective.

It will be noted that members 35 may occupy three different positions at different times, the uppermost being shown in Fig. 11, the intermediate one being shown in Figs. 8 and 9 and the lowermost one being shown in Fig. 10.

At certain points in the cycle, one or more yarn carrier rods, and in this instance rod 4, need to be held from moving even though coupled to their friction boxes in order to permit an idle course movement or for other purposes. The fact that members 35 may occupy three different positions permits one or more of them to be used for locking purposes and the rod 4 therefore is provided with a high dog 39 (Fig. 3) similar to dog 41, but placed so that it can engage a member 35, if it is not in too high a position. The rod to be locked, such as rod 4, in this instance, is locked in its right hand position, and by suitably setting the buttons on the main pattern chain, the members 35 may be operated at the proper time to lock the carrier rod or to control the length of stroke of a carrier rod as desired. Therefore, to control the locking of such rod or rods, it is then necessary only to lower the members 35 into engagement with the dog or dogs 39 thereon. By raising members 35 at the proper time, the rod 4, or any one of the carrier rods that may have a high dog 39 thereon, are released and permitted to make a yarn laying stroke. While I have found it convenient and, for certain reasons set out hereinbelow, prefer to provide three positions for the member 35 and have so shown them it will be seen that this is not absolutely necessary and that the members 35 need have only two positions, one shown in Figs. 8 and 9, and the other shown in Fig. 10.

The mechanism for positioning the members 35 in carrying out a desired knitting cycle is shown in detail in Figs. 2, 3, 6 and 7. The arrangement of this mechanism includes a rigid arm 43 which is fixed to a rear horizontal frame member 44 and extends upwardly and forwardly therefrom. The block 36 mentioned hereinabove has a rearwardly extending arm 64 which is fixed to the upper forward end of arm 43 and a lifting bar 45 is provided which is mounted to move relative to the carrier rods, being pivoted at one end to a link 46 and at its other end to a link 47 which is arcuate or curved through a considerable arc to permit it to swing on its pivot to the degree required by the movements of members 35 without interfering with other members of the machine. Link 46 is pivoted to block 36 at 48 and link 47 is pivoted at 49 to plates 38 cast integral with the upper end of

arm 43, a pin 59 being provided to pin the rear arm 64 of block 36 to arm 43. The bar 45 extends from link 46 to link 47 beneath inwardly projecting dogs 50, one on each of a group of handle pieces 51 provided one at the upper end of each stop or locking bar 35. A rocking motion of links 46 and 47 in one direction therefore moves bar 45 away from the carrier rods to lift members 35 while a rocking motion of these links in the other direction permits members 35 to move downward toward bars or carrier rods under the influence of springs 52. Springs 52 extend between outwardly projecting pins 53 on side plates 37 and outwardly projecting noses 54 on handles 51. 15

The means shown for swinging or rocking links 46 and 47, thereby moving stop or locking members 35, comprises a lever 55 which is pivoted at a point intermediate its ends to a bracket 56. Lever 55 preferably extends up to the level of the top of link 47 or thereabout and at its upper end, is connected by a link 57 with a lug 58 on the upper portion of curved link 47 so that an oscillating movement of lever 55 on its pivot causes link 47 to move link 46 and bar 45 and thereby the members 35. A spring 61 is connected between a hook 62 on lever 55 above the pivot point of the lever and a pin 63 fixed to the arm 43 and tends to pull the upper end of lever 55 forward, to the right in Fig. 3, to lower members 35 while a roller 65 at the lower end of lever 55 bears against a camming means 66 shown as including an auxiliary or supplemental pattern chain 66, the links of which determine, in connection with spring 61, the angular position of lever 55 and thereby the height of members 35 from the carrier rods. Chain 66 is shown as passing around and extending horizontally from wheel 67 and as having links of three different heights. The roller 65 is shown in Fig. 3 as pressing against a link 68 of least height. Members 35 are then in their lowest position, corresponding to Fig. 10. If wheel 67 is turned one link distance in the clockwise direction from the position shown in Fig. 3, roller 65 then will bear on a link 69 of intermediate height. The members 35 will then be in their intermediate position corresponding to that shown in Figs. 8 and 9. Several additional steps of wheel 67 will then bring one of the highest links 70 in contact with the roller 65 and the members 35 are then at their highest position as shown in Fig. 11. 45

The wheel 67 is mounted on an auxiliary cam shaft 72 and means 73 are provided for racking the shaft 72 to step the wheel 67 automatically under control of the main pattern chain 25. Means 73 comprises a bell crank lever 74 (Fig. 2) swivelled or pivoted on a shaft 75 and having one arm extending forwardly almost horizontal when inactive and the other arm extending upwardly almost vertical when inactive. The vertical arm of lever 74 carries a roller 76 arranged to contact, when the lever is inactive, the portion of larger radius of a cam 71 on shaft 12. The upper end of lever 74 is pivoted to a link 77 at the front end of the link while the rear end of link 77 is pivoted to a racking arm 78 swivelled on shaft 72. A finger 79 extending downwardly from the rear end of link 77 is connected to the rear end of a spring 81, the forward end of which is connected to an upstanding finger 82 fixed to a back beam 83. The stress of spring 81 is transmitted through link 77 to throw the vertical arm of lever 74 forward whenever permitted. A lever 84 pivoted on a front beam 85 so as to swing in a hori- 70 75

zontal plane is arranged to pass beneath the forward end of the horizontal arm of lever 14 to hold it against the tension of spring 81 and thereby to prevent lever 14 from swinging on its pivot. The 5 lever 84, is connected to one of the horizontal rods 86 extending along the front of the machine and which are operated by the main pattern chain 25. Said rod 86, connected to lever 84, is actuated at proper times by chain 25 to withdraw it from beneath lever 14. Spring 81 thereupon forces roller 76 to follow cam 71 throughout its perimeter and cam 71 has a low spot permitting spring 81 to throw the vertical arm of lever 14 forward and back once each revolution of 10 the cam whenever lever 14 is unimpeded. Arm 78 is oscillated whenever lever 84 is operated and a pawl 87 pivoted on arm 78 is operated to rack a ratchet wheel 90 fixed to shaft 72 and thereby step shaft 72 and change the position of chain 20 66. A clock pawl or ratchet 91 holds the wheel 90 against return movement.

The chain 66 is shown in Fig. 12 arranged parallel to a stocking blank 92 of a full fashioned stocking, the upper dot-and-dash-line portion of 25 the blank indicating the portion of the blank which is knitted first and afterward turned or folded to form a two ply welt according to the common practice. From Fig. 12, it is apparent that low or narrow links 68, positioning members 30 35 in their lowest position, are used only at two periods in the cycle of knitting blank 92, one period for holding carrier rod 4 in its laid out position in which it is held by engagement of the dog 39 with one of the members 35 between such member and a usual stop for determining 35 the laid out position of the carrier rod after the knitting of the ravel course portions 93 at the ends of the heel tabs 94 of the blank and another after the first course of a welt 95 has been laid. 40 Fig. 12 indicates also that the members 35 occupy their intermediate positions at only one period during the cycle, or at the beginning of the welt 95. After resetting of the nuts 21 and 29 has been completed and throughout the remainder 45 of the cycle only links 70 of greatest height are used, thereby maintaining the members 35 in their uppermost positions in which they are entirely inactive.

It will be seen that the reasons for having three 50 positions of the positioning members 35 are that in their highest position they may be fully protected against contact with other objects by the parts 36 and 37 and do not offer any interference to the dogs or projections such as 41 or 42, while 55 in their lowest position they intercept not only the high dogs but the low ones, and in their intermediate positions they intercept the high dogs and allow the low dogs to pass.

Of course, the improvements specifically shown 60 and described by which I obtain the above results, can be changed and modified in various ways without departing from the invention herein disclosed and hereinafter claimed.

I claim:

65 1. In a knitting machine having a main shaft and means to shift said shaft from knitting to narrowing position and back, the combination with a yarn carrier rod and end stop therefor movable in the path of the rod to vary its traverse 70 and also movable out of the path of the rod to permit the rod to be operated full stroke at a time when the end stops are being moved longitudinally of the path of the rod, of projections extending outwardly from one edge of said rod, auxiliary 75 stop means including a device movable into the

path of said projections, a pattern chain, an auxiliary chain having links of unequal height in the plane of the chain, means controlled by links of said auxiliary chain for throwing said device into and out of the path of said projections, and means 5 controlled by said pattern chain independently of the position of said shaft for stepping said first chain to time the action of said auxiliary stop means.

2. In a knitting machine, the combination as 10 set forth in claim 1 and in which the yarn carrier rod is arranged to be laid out at one side of its path of normal travel and the means for controlling the auxiliary stop means are arranged to throw the auxiliary stop means into action as the 15 rod moves out of its laid out position.

3. In a knitting machine, in combination, a yarn carrier rod mounted to reciprocate in laying yarn, stops adjustable to vary the traverse of said rod, said rod being adapted to be laid out at one 20 side of the path of travel it uses in laying yarn, means to move said stops to increase the distance therebetween at a point in the operation of the machine, said rod being movable from its laid out position while said stops are being moved apart, 25 an auxiliary stop means, and means arranged to cause said auxiliary stop means to catch said rod upon its initial movement away from its laid out position.

4. In a knitting machine, the combination as 30 set out in claim 3 and in which the rod has a pair of dogs thereon, one of which projects farther from the rod than the other to cooperate with the auxiliary stop means.

5. In a straight knitting machine having a 35 group of parallel carrier rods, in combination, end stops for said rods movable into and out of the paths of the rods, auxiliary stop and lock members for cooperating with said rods mounted to move at right angles thereto, means urging said 40 members toward said rods, and means for moving said members against said urging means and for determining the position taken by said members comprising a bar transverse to but parallel to the upper edges of said rods and engaging said 45 members, a parallel motion for moving said bar, a camming means controlling the action of said parallel motion, a main cam shaft, means for transmitting racking impulses from said cam shaft to said camming means, a pattern chain, 50 and means for controlling said impulse transmitting means from said pattern chain.

6. In a knitting machine, the combination with a yarn carrier rod, pattern means and means for advancing said pattern means, of a plurality of 55 dogs on said rod, a device for engaging one of said dogs in only one of three positions of the device laterally of the rod and engaging another of said dogs in either of two of said positions, and means controlled by said pattern means for moving said device to and from each of said three positions relative to another.

7. In a knitting machine, the combination with a yarn carrier rod, main pattern means, and means controlled by said main pattern means for 60 actuating auxiliary pattern means, of a plurality of dogs on said rod, a device for engaging one of said dogs in only one of three positions of the device laterally of the rod and engaging another of said dogs in either of two of said positions, and 70 auxiliary pattern means actuated by said actuating means for moving said device to and from each of said three positions relative to another.

8. In combination in a full fashioned knitting machine, a cam shaft, yarn carrier rods mounted 75

- for longitudinal reciprocation and carrying stop
cooperating elements of different heights from
the rods intermediate the ends thereof, plunger
stops movable transversely to the rods into and
5 out of the paths of movement of said stop ele-
ments, stationary means bridged across the rods
for positioning the plungers, movable means
bridged across the rods for controlling the posi-
tions of the plungers relative to said stop co-
10 operating elements, an auxiliary control shaft,
camming means advanced by said auxiliary con-
trol shaft for giving said movable bridging means
at least three different positions, and means con-
trolled by said main pattern device for causing
15 said cam shaft to advance said auxiliary control
shaft.
9. In a knitting machine, the combination as
set forth in claim 3, and in which a pair of pro-
jections of different lengths fixed on the rod co-
20 operate with the auxiliary stop means and means

to move said auxiliary stop means toward said rod
in two steps in the first of which engagement
occurs only with the longer of said projections.

10. In a full fashioned knitting machine hav-
ing a main cam shaft and pattern controlled 5
means for shifting said shaft from knitting to
narrowing position and back, the combination
with a yarn carrier rod mounted to reciprocate
and having a projection intermediate its ends ex-
tending from one edge thereof, a device movable
into and out of the path of said projection, a pat-
tern means, a camming means, means controlled
by said camming means for throwing said device
10 into and out of the path of said projection, and 15
means controlled by said pattern means inde-
pendently of the position of said shaft for racking
said camming means to time the action of said
throwing means.

MAX RICHTER. 20
